(57) **CLAIM**

The ornamental design for a robot for guiding people, as shown and described.

DESCRIPTION

FIG. 1 is a front perspective view of a robot for guiding people showing our new design;

FIG. 2 is a front view thereof;

FIG. 3 is a rear view thereof;

FIG. 4 is a left side view thereof where the right side view is a mirror image;

FIG. 5 is a top plan view thereof; and,

FIG. 6 is a bottom plan view thereof.

The broken lines depict portions of the robot for guiding people that form no part of the claimed design.

1 Claim, 6 Drawing Sheets
